UNITED STATES PATENT OFFICE

FRANK AULT, OF SALEM, OHIO, ASSIGNOR TO THE SALEM POTTERY COMPANY, OF SALEM, OHIO, A CORPORATION OF OHIO

APPARATUS FOR UNDERGLAZE DECORATING PRINT WARE

Application filed March 4, 1931. Serial No. 519,966.

The invention relates to pottery ware having decorations thereon under the glaze coat, and more particularly to apparatus for transferring a printed design onto the ware before it is dipped into the glaze.

Pottery ware which has been fired once, and before it has been glazed is commonly known as biscuit ware. It has been found that a design printed on tissue paper and the like may be transferred to biscuit ware by placing the paper with the printed side down upon the biscuit ware, and then covering the paper with soft soap and rubbing over the same with a brush or a piece of flannel.

However, it is necessary to apply a considerable force in the rubbing operation and a large amount of manual labor is involved, making the rubbing operation a tiresome and tedious process.

Accordingly, it is an object of the present invention to provide a simple and compact apparatus for economically applying a rubbing or brushing action to the back of the printed paper when it is placed in position on the biscuit ware, whereby the decorative design will be properly and uniformly transferred to the ware in a relatively short time.

Another object is to provide improved means for bringing the ware into operative position relative to the rubbing element after the printed paper is positioned upon the ware.

These and other objects are attained by the parts, combinations and improvements which comprise the present invention, and which may be stated in general terms as including a supporting frame, a drive shaft, means on the frame for rotating the drive shaft, a rubbing element on the drive shaft, a non-rotating table for supporting the ware and normally spaced from the rubbing element, and means for moving the table to bring the ware into contact with the rubbing element.

A preferred embodiment of the present improvements is illustrated in the accompanying drawings, in which

Figure 1 is a front elevational view of the improved apparatus showing a piece of

ware in position upon the supporting table and in contact with the rubbing brush;

Fig. 2 is a side elevation thereof; and

Fig. 3 is a side elevation similar to Fig. 2 with the ware removed and the table in operative position relative to the brush.

Similar numerals refer to similar parts throughout the several views.

The apparatus indicated generally at 10 includes a supporting frame 11, which preferably is vertically disposed and may be supported on a suitable base indicated generally at 12. The frame 11 may be constructed of angle bars and the like, and is preferably braced as shown at 13 to maintain the frame 65 rigid.

Means for rotating the rubbing element may include a motor mounted on the upper end of the frame 11 and enclosed in a suitable housing 14. A starting switch 14a is 70 preferably provided for operating the motor.

The motor rotates the vertical shaft 15 journaled in the housing 14, and a rubbing element indicated generally at 16 is secured 75 upon the lower end of the shaft 15. This rubbing element is preferably in the form of a brush 17, having its bristles shaped to fit the inner contour of the article to be decorated, as best shown in Fig. 3.

Means for supporting the ware preferably includes a table 18 fixed upon the upper end of a vertical shaft 19 below and axially aligned with the shaft 15. The upper surface of the table 18 is preferably covered 85 with friction material as indicated at 20, in order to prevent the ware from turning on the table when the brush 17 is in contact with the ware.

The shaft 19 is mounted for vertical sliding movement and against rotation upon the lower portion of the frame 11. The means for mounting the shaft may include a supporting bracket 21 secured to the frame as by bolts 22, and having the spaced upper and lower shaft bearings 23 and 23' respectively, in axial alignment with the shaft 15. The shaft 19 may be slidably keyed in these bearings to permit vertical sliding movement 95 without rotation of the shaft.

Means for raising the table 18 to bring the ware thereon in contact with the brush 17, may include a pinion gear 24 rotatively mounted upon the supporting bracket 21, and adapted to mesh with the rack portion 25 on the inner side of the shaft 19.

The gear 24 is preferably fixed upon a spindle 26, which spindle is journaled in the bracket 21 and extends laterally outwardly therefrom. A lever arm 27 is secured at one end to the outer end of the spindle 26, and has a slot and pin connection at its other end with the manually operated lever 28, as indicated at 29.

The lever 28 preferably has its upper end pivotally connected to the upper end portion of the bracket 21 as shown at 30.

A stop 31 may be secured to the shaft 19 to limit its downward movement by abutment of the stop with the bearing 23' when the table 18 is in the position shown in Fig. 3.

When it is desired to transfer a design which is printed upon tissue paper and the like to a piece of biscuit ware, the paper is placed printed side downward upon the upper surface of the ware, in proper relative position to the contour of the ware. The parts of the improved apparatus are normally in the position shown in Fig. 3 due to the effect of gravity upon the table 20 and shaft 19. When the printed paper having the desired design thereon has been properly applied to the ware as above set forth, the back of the paper is covered with a soft soap and the ware is placed upon the table 20 in the central portion thereof, the table occupying its normal position as shown in Fig. 3.

After starting the motor to rotate the brush, the operator then exerts an inward pressure on the lower end of the lever 28 moving the same inward toward the frame 11. This inward movement of the lever 28 rotates the lever arm 27 inwardly and also the gear 24. Rotation of the gear 24 in a clockwise direction as viewed in Figs. 2 and 3 carries the shaft 19 and table 20 upwardly until the ware is in contact with the brush 17, the bristles fitting into the contour of the ware so as to exert a uniform pressure over all parts of the printed paper.

Thus it will be seen that a simple and effective apparatus is provided for exerting a uniform pressure upon the printed paper when in position on the ware for any desired length of time, and the improved means for raising and lowering the table provides for varying the pressure exerted as desired.

Obviously such an apparatus achieves a great saving in labor and expense, and it has been found that a higher quality article is produced by the use of such apparatus than by the old manual methods.

I claim:

1. Apparatus for transferring printed decorations to pottery ware including, a

frame, a rubbing element rotatively mounted on the frame, means for rotating the rubbing element, non-rotating means coaxial with the rubbing element and normally spaced therefrom for supporting the ware, and means for axially moving the supporting means toward the rubbing element. 70

2. Apparatus for transferring printed decorations to pottery ware including, a frame, a brush rotatively mounted on the frame and having its bristles shaped to fit the contour to the ware to be decorated, means for rotating the brush, non-rotating means coaxial with the brush and normally spaced therefrom for supporting the ware, and means for axially moving the supporting means toward the brush. 75

3. Apparatus for transferring printed decorations to pottery ware including, a frame, a rubbing element rotatively mounted on the frame, means for rotating the rubbing element, a shaft axially aligned with the rubbing element, a table fixed on the shaft and normally spaced from the rubbing element, means slidably and non-rotatively mounting the shaft upon the frame, and means for axially moving the table toward the rubbing element. 80 85

4. Apparatus for transferring printed decorations to pottery ware including, a frame, a brush rotatively mounted on the frame and having its bristles shaped to fit the contour of the ware to be decorated, means for rotating the brush, a shaft axially aligned with the brush, a table fixed on the shaft and normally spaced from the brush, means slidably and non-rotatively mounting the shaft upon the frame, and means for axially moving the table toward the brush. 90 95

5. Apparatus for transferring printed decorations to pottery ware including, a frame, a brush rotatively mounted on the frame and having its bristles shaped to fit the contour of the ware to be decorated, means for rotating the brush, a shaft axially aligned with the brush and having a rack portion thereon, a table fixed on the shaft and normally spaced from the brush, a pinion meshing with the rack portion of the shaft, and lever means for rotating the pinion to axially move the table toward the brush. 100 105 110

In testimony that I claim the above, I have hereunto subscribed my name.
